James P. Duhamel,
ATTORNEY.

INVENTOR.

UNITED STATES PATENT OFFICE

JACOB D. STIRISS, OF NEW YORK, N. Y.

POWDER BOX

Application filed November 1, 1928. Serial No. 316,467.

This invention relates to powder boxes and its object is to provide said boxes with a powder dispenser located below a hinged partition having an opening in which the dispenser plays, the latter consisting of an endless belt encircling an endless sheet metal frame held between rigid lugs extending from the bottom of the box and clamped by means of the hinged partition.

10 A further object of the invention provides for the opening of the hinged partition to refill the box without interfering with the carrier frame and the belt which remains in place between the lugs extending from the 15 bottom of the box although removable if desired to repair any damage to the belt.

Another object is to provide an endless sheet metal frame as a belt carrier so constructed as to prevent the accumulation of 20 powder between the belt and carrier, due to springing the latter and retarding the movement of the belt.

A further object of the invention is to locate the mirror in such manner that the 25 face of it will be upward whether swung to one or the other compartment of the vanity case, and when swung to one compartment will clear the other entirely.

These and other objects and details of the 30 invention are more fully described in the following specification, set forth in the appended claims and illustrated in the accompanying drawings, wherein:

Fig. 1 is a plan view of the open box with 35 the mirror down.

Fig. 2 is a longitudinal sectional view through the box.

Fig. 3 is a cross sectional view through the closed box.

40 Fig. 4 is a perspective view of the mirror support.

Fig. 5 is a perspective view of the belt carrier raised from its supports.

Fig. 6 is a plan view of the puff platform.

45 A serious difficulty has been found in the use of powder boxes where manipulating parts are employed on account of the waste and spilling of the powder when the box is refilled. Very few of the purchasers and 50 users of these boxes possess sufficient me-

chanical knowledge to remove or replace those parts which give access to the interior of the powder chamber or to know or find how the powder is deposited.

Another serious difficulty experienced in 55 boxes of the type described and as heretofore made is the tendency of the powder to pack about the operating parts and cause them to bind. The parts will thereby fail to move or deliver powder, resulting in the waste of 60 time and breakage of parts. Where swinging or oscillating mirrors are used for these devices, they were not made so as to easily be placed when in use in one or the other compartment face up so as not to interfere 65 with the compartment in use.

To overcome these objectionable features the interior of the box 10 and its lining 11 are made readily accessible by hinging to the latter a platform 12 having an opening 13 70 through which plays the endless belt 14 that carries the powder from the box to the outer surface level of the platform 12.

The belt 14 is loosely carried by a sheet metal frame 15, whose construction is best 75 shown in Fig. 5, and is located below the opening 13 of the platform 12. The frame 15 has wings or extensions 16 at each side which are clamped by the edges of the opening 13 against the shoulders 18 of the standards 17 and hold the frame and belt rigidly in place.

Rising from the surface of the lining 11 are standards 17 to form a support for the frame 15 adjacent the opening 13 of platform 12, and which show in dotted lines in 85 Fig. 6. Shoulders 18 are cut at the top of these standards into which fit the ends of the wings 16 and the frame is thus supported while held firmly in place by the platform and the belt will move freely 90 with same carrying up the powder from either one side or the other.

The upper ends of standards 17 fit into and project slightly above recesses 13' of 95 opening 13. The object is to keep the standards in alignment with the edges of opening 13, to prevent the standards from bending, and lock the whole unit in place.

The standards 17 are made to clamp the 100

sides of frame 15 holding the latter in place when platform 12 is raised for refilling.

The platform 12 fits snugly within the upright edge 19 of the lining 11 to which it is hinged and opposite the hinge 20 is a lip 2, to raise or lower the platform.

The lid 22 comprises a similar section of the box 10 to which it is hinged at 23 and secured to it by the spring catch 24 on the box and engaging a notch 25 in the lid. The latter carries the rouge cake 26 and on the pintle of the hinge 23 is hung a yoke 26 in which is pivoted the mirror 27.

The yoke 26 is so shaped that it will lie flat in one or the other compartment, the mirror therefor will rest on puffs 28 or 29 as required without obstructing any part of the compartment in use, the yoke being offset and located centrally between the two compartments.

The mirror may be compactly stored in the device as shown in Figs. 1 and 3 or elevated to the position shown in Fig. 2, and placed in one or the other compartment as required.

Puffs 28 and 29 may be provided for the rouge 30 and the powder respectively, and the mirror may be used to hold one or the other down when not being used.

In using the powder box, a supply of powder may be gathered up by the puff 29 from the belt that is made of a material adapted to gather up the powder when travelling through it. When the supply of powder is removed from the belt, the latter may be drawn over the frame 15 by the puff until a section of the belt with a covering of powder is presented in the opening 13.

When the supply of powder is exhausted the platform 12 is raised and without disturbing any other part of the device, the powder may be placed in the empty spaces in the box. In this operation the frame 15 and the belt 14 remain supported on the standards 17 and held in the shoulders 18 against any movement and with no chance of accidental removal because the frame 15 is held frictionally against the sides of standards 17.

The frame 15 is made of a single piece of sheet metal and its ends hooked together to prevent distortion of its size and shape as shown in the drawings and wings may be made to the platform 12 at the sides of opening 13 to co-operate with the wings 16 of frame 15.

It is evident that the parts of this device may be otherwise arranged or modified without departing from the essential features above described, or from the scope of the appended claims.

What I claim as new is:

1. In a powder box, the combination of a box for containing powder, a platform having an opening, powder carrying means exposed by the opening, and supporting means for the platform and the powder carrying means.

2. In a powder box, the combination of a box for powder, a platform to cover the powder and having an opening, powder carrying means playing in the opening, and uprights from the bottom of the box and adapted to support the platform and the powder carrying means.

3. In a powder box, the combination of a box adapted to contain powder, an endless belt for carrying the powder, a frame encircled by the belt, and uprights supporting the frame and adapted to prevent lateral movement of the same.

4. In a powder box, the combination of a box adapted to contain powder, a frame carrying an endless belt, uprights from the box to support the frame and prevent lateral or longitudinal movement of the said frame, and a platform having an opening to expose the belt and adapted to confine the frame within the box.

5. In a powder box, the combination of a box adapted to contain powder, a sheet metal frame, an endless belt encircling said frame and adapted to be moved around same, a platform having an opening for the belt and adapted to confine the frame within the box, and uprights adapted to support the platform and having shoulders on which the frame is lodged and restrained from lateral or longitudinal movement.

6. In a powder box, the combination of a powder box, a lining for the same, a platform hinged to the lining and having an opening, uprights supporting the platform, an endless sheet metal frame carrying an endless belt and located beneath the opening of the platform and between the uprights, wings at the sides of the frame, and shoulders on the uprights supporting the said frame and preventing lateral and longitudinal movement.

7. In a powder box, the combination of a box for containing powder, a platform having an opening and covering the powder, a frame within the said opening and having side wings engaged by the edges of the opening, standards adapted to support the platform and frictionally engaging the sides of the opening therein and at the same time frictionally engaging the sides of the frame, a joint in the frame adapted to present a smooth outer surface for same, and an endless belt on the frame and adapted to be moved in the opening of the platform.

In testimony whereof I hereunto affix my signature.

JACOB D. STIRISS.
